(57) **CLAIM**

The ornamental design for a “portable power sprayer for spraying wax onto vehicles,” as shown and described.

DESCRIPTION

FIG. 1 is a front perspective view of a “portable power sprayer for spraying wax onto vehicles” showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a perspective view similar to FIG. 1 showing the manner in which the invention supports auxiliary items. The matter shown in phantom in FIG. 8 is for environmental purposes only and does not form a part of the design.
